CALENDAR

Harry E. Kranhold, St. Paul, Minn.

Application September 27, 1937, Serial No. 165,791

3 Claims. (Cl. 40—119)

My invention relates to an improvement in calendars of a type designed to permit the retaining of the calendar sheets throughout the year without in any way affecting the appearance of the calendar.

Calendars have previously been formed in the shape of a book of sheets, some of the sheets of which contain calendar indicia. Various ways have been employed to fold the sheets over in order than memorandums written on the rear of the sheets or other data incorporated on the sheets with the calendar indicia may be retained. It has usually been necessary, however, in such constructions, to provide a different display to be used in conjunction with each sheet of the calendar in order to permit the various sheets to be folded over at the end of the month to display a new sheet. While this construction has the advantage of providing a series of varying displays during the year, it has the disadvantage of being costly to manufacture. These calendars also ordinarily have the disadvantage of not folding entirely flat, and therefore get somewhat out of shape before the end of the year.

It is an object of the present invention to provide a calendar formed in two parts, one of which provides a permanent display which may be used throughout the entire year, and the other part of which forms the calendar pad. This calendar pad is preferably bound by means of a spiral binder or a ring or plastic binder, so that the calendar sheets may be folded over onto the back of the calendar pad and will remain flat whether the sheets overlie the front or back. The two parts of the calendar are pivotally connected together in such a way that the sheets of the calendar pad portion may be folded back and retained throughout the entire year.

It is a purpose of my invention to provide a calendar having a display portion and a calendar pad portion pivotally attached adjacent the binding of the pad sheets. This permits the pad to be supported adjacent its binding and to lie flat in proper position.

It is a further object of my invention to provide a calendar pad connected to a display portion in such a way that although the connection supports the pad adjacent the binding, the sheets may be folded from position overlying the front of the pad, to position overlying the rear pad surface. This I accomplish by providing a loop or a pair of oppositely disposed arms which are pivotally connected to the display portion at a distance from the edge thereof adjacent the

calendar pad. These arms or this loop are pivotally connected to the pad portion adjacent the binding, to support the pad suspended closely adjacent the display portion. This construction enables the pad to be swung outwardly to a considerable distance from the display portion to permit the sheets of the pad to be folded over between the pad and the display portion to overlie the back of the pad.

These and other objects and novel features of my invention will be more clearly and fully set forth in the following specification and claims.

In the drawings forming a part of my specification:

Figure 1 is a front elevation view of my calendar.

Figure 2 is a rear elevation view of the calendar illustrated in Figure 1.

Figure 3 is a perspective view of my calendar, with the uppermost sheet thereof being folded back to overlie the back of the pad and to expose the next uppermost sheet to view.

Figure 4 is a front elevation view of a slightly different form of pad supporting loop from that illustrated in Figures 1 through 3.

Figure 5 is a detail view of a portion of the rear of a calendar illustrating the supporting loop illustrated in Figure 4 in proper position.

Figure 6 is a detail view of a portion of the rear of my calendar, illustrating the display portion and the supporting device for the pad.

Figure 7 is a cross-sectional view, taken on the line 7—7 of Figure 6.

Figure 8 is a front elevation view of a slightly modified form of calendar construction.

Figure 9 is a side elevation view of the calendar illustrated in Figure 8.

Figure 10 is a front elevation view of a slightly different form of construction of supporting loop.

The calendar A comprises an upper display portion 10 and a lower calendar pad 11 connected to the upper portion 10 by means of a supporting loop 12. The upper portion 10 is provided with an advertising picture or any type of illustration or indicia which may be desirable for display throughout the entire year.

The lower calendar portion 11 comprises a series of sheets 14 which are connected together to form a pad by means of a spiral binding 15. As will be clearly understood, the binder 15 extends through regularly spaced openings in the top of the sheets 14 and holds the sheets 14 flat, one upon the other, whether one sheet is in front or whether any other sheet is in display position.

The loop 12 illustrated in the drawings, com-

prises a substantially U-shaped member having a closed transverse end 16 which is transversely connected to the display portion 18 by means of a suitable tape 17 or the like. The manner in 5 which the tape incloses and pivotally supports the loop 12 may best be seen in Figure 2 of the drawings. The loop 12 is provided with oppositely disposed parallel arms 19 which have in-turned ends 20 thereupon. These inturned ends 10 20 extend into the ends of the spiral binder 15 and pivotally connect the loop 12 to the pad portion 11.

Figure 1 illustrates the calendar as it would appear throughout the first month of the year 15 supported on a suitable nail or hock, not illustrated in the drawings, extending through the opening 21 at the top of the display portion 10. At the end of the month, the outermost sheet 20 14 is folded back to underlie the remaining sheets of the pad. This is accomplished by pivoting the loop 12 so that the arms 19 extend at a substantial angle with respect to the display portion 10 and the outermost sheet inserted in the opening between the pad 11 and the display 25 portion 10. The manner of holding the calendar pad during this movement is illustrated in Figure 3 of the drawings, where one end is shown holding the display portion 13 angularly disposed with respect to the pad 11 and the outermost sheet 14 is being drawn through the opening 30 between the upper and lower portions of the calendar. The spiral binding maintains the rear sheet flat, as well as the front sheet of the pad.

In Figures 4 and 5 I disclose a slightly different 35 form of calendar construction. In this form of calendar B, the upper display portion 22 and the calendar pad 23 are substantially identical to the form previously described. A spiral binding 24 holds the sheets of the pad 23 together.

40 In this form, however, a supporting loop is provided which is substantially U-shaped. This supporting loop 25 is provided with a closed end 26 which extends through the spiral binder 24 and which extends upwardly at 27, forming a pair 45 of oppositely disposed supporting arms. The ends 29 of the arms 27 are bent inwardly and extend through a transverse journal 30 on the clip 31, which clip is fastened to the display portion 22 of the calendar by anchoring lips 32. The 50 tips of the ends 29 are bent backwardly upon themselves as indicated at 33, so as to hold the loop 27 in proper engagement with the clip 31.

In Figures 6 and 7 of the drawings, I disclose 55 a calendar C. This form of calendar provides a display portion which extends from the lower edge 34 adjacent the spiral binder 35 upwardly to the top edge of the display. The calendar then folds downwardly and the extreme end of this portion of the calendar is bent inwardly and upwardly at 36. Clips 37 or the like, extend through the front panel portion 38, the downwardly extending flange 39 extending down from the top of the sheet 38 and the upwardly extending portion 36 of the calendar to hold these portions 60 securely together.

65 A loop 41 is provided to hold the pad portion 42 to the upper portion 39 of the calendar. This loop 41 is secured to one of the sheets 43 forming the pad 42 by means of tape 44 which is adhered to the sheet 43 and which extends over the transversely extending portion 45 of the loop 41. The 70 loop 41 is provided with oppositely disposed side arms 46 having in-turned ends 47 which extend between the upturned end 36 and the portion 40 of the calendar. The extreme end 49 of the loop 75

41 is bent at right angles to the portion 47 and extends out through a notch 50 in the fold between the portions 36 and 40 to hold the loop 41 properly in place.

With this construction, the loop 41 may be 5 readily inserted in place after being preformed and the loop may be attached to the pad by tape and need not be extended through the binding member.

In Figures 8 and 9, of the drawings, I illustrate 10 a permanent type of calendar. This device comprises a display portion 51 having a suitable picture or other indicia thereupon. A pair of ears 52 extend rearwardly from the back of the display portion 51 to support the ends of the 15 wire loop 53. This loop 53 extends through the rings 54 of the binder which supports the sheets 55 forming the calendar pad 56. The sheets 55 in this construction are formed of relatively stiff material such as cardboard, so that they may 20 be used time after time and accordingly in order to avoid the necessity of bending these cards as they are turned, the loop 53 is of sufficient length to permit the sheets 55 to be turned to overlie the back of the binder without bending these 25 sheets. The sheets 55 preferably bear indicia from 1 to 31, and may be used continuously month after month.

In Figure 10 of the drawings, I show a modified form of loop 57 of substantially a U-shape, 30 having a closed end 59 and side arms 60. The closed end 59 is adapted to be supported to the display portion of the calendar by tape, as illustrated in Figure 2 of the drawings, or this portion 59 may extend through the fold between 35 the portions 36 and 40 of the calendar C. The ends 61 are looped or are hook-shaped to connect onto the ends of whatever type of binding is used.

The operation of my calendar is believed clear 40 from the foregoing description. When it is desired to turn a sheet of the calendar it may be done as best illustrated in Figure 3 of the drawings. When the sheet has been properly turned, the calendar may be supported by inserting the 45 same over a suitable supporting nail or the like.

In accordance with the patent statutes, I have described the principles of construction of my calendar, and while I have endeavored to set forth the best embodiments thereof, I desire to 50 have it understood that this is only illustrative of a means of carrying out my invention and that obvious changes may be made within the scope of the following claims without departing from the spirit of my invention. 55

I claim:

1. A calendar comprising a supporting portion, a calendar pad portion comprising a series of sheets, a binder for said sheets, and means 60 swingably connecting said calendar pad portion to said supporting portion, said connecting means comprising arms pivotally connected to said supporting portion at a point spaced from the lower edge thereof and pivotally connected to said binder to support said calendar pad portion normally suspended below said supporting portion, and means on said arms limiting the pivotal movement between said arms and said supporting portion to assist in maintaining said arms in normal substantial alignment with said supporting portion.

2. A calendar comprising a supporting portion, a calendar pad portion, a binder for said calendar pad portion, loop means connecting said binder and said supporting portion, and means se- 75

curing said loop means pivotally to the rear surface of said supporting portion, said loop extending beyond the side and bottom edges of said supporting portion.

5. 3. A calendar comprising a supporting portion, a calendar pad portion and means connecting said pad portion to said supporting portion, said connecting means comprising a loop pivotally

connected to the top of said calendar pad portion and to said supporting portion, substantially centrally between the top and bottom edges thereof, and means securing said loop pivotally to said supporting portion on the back of said supporting portion, said loop extending beyond the opposite side edges of said supporting portion.

HARRY E. KRANHOLD.
